UNITED STATES PATENT OFFICE

GEORGE A. DICKLEY AND EARL B. GROFF, OF LONG BEACH, CALIFORNIA

ADJUSTABLE PLATEN-PRESS CHASE

Application filed December 24, 1928. Serial No. 328,110.

In two or more color printing, on ruled blanks, and all other classes of printing where an accurate register is desired, it very frequently occurs that after a form has been made ready, gauge pins secured and sealed, it is necessary in order to correct the register, that the seals be broken and the pins moved. This results in a considerable loss of time and a weakening of the tympan for the further securing of gauge pins.

Also in printing where a heavy rule or a heavy line of type extends vertically across the form it is found that sufficient distribution of ink is not ordinarily maintained and some crude or lengthy method is adopted to overcome this difficulty.

It is also necessary, in some classes of printing to secure the form on the bed of the press so that it will be held in one fixed position during the process of printing.

It is the prime object of our invention to provide a platen press chase which will permit the form, when on the press to be moved in any direction on the bed thereof, which will permit either end to be adjusted independently of the other end, and to provide a simple, positive, speedy and accurate means of locking the chase upon the bed of the press.

A further object is to provide a simple and efficient means of adjusting the form at a slight angle to obtain better and more even distribution of ink on a heavy rule or heavy line of vertically extending type, and in the case of rule forms to reduce to the minimum the damage to the ink rollers while printing such forms.

A further object is to provide mechanism of the above character which can be added to or made a part of platen press chases now in use or which can be embodied in the same when manufactured.

Other objects and advantages will appear hereinafter and, while we have shown and will describe the preferred form of our invention we wish it to be specifically understood that we do not limit ourselves to such preferred form but that various changes and adaptations may be made therein without departing from the spirit of our invention.

In the drawings accompanying and forming a part hereof:

Fig. 1 is a front elevation of a platen press chase embodying our invention.

Fig. 2 is a fragmentary view of the left hand end of Fig. 1 showing our improvement in its operative position.

Fig. 3 is a section on the line 3—3 of Fig. 2.

Fig. 4 is a section on the line 4—4 of Fig. 2.

Fig. 5 is a view similar to Fig. 4 but in its inoperative position.

Referring to the drawings 6 indicates a platen press chase of any usual or ordinary type of construction; 7, 8, indicate the usual roller tracks, and 9, 10 the usual lugs or abutments against which the lower edge of the chase rests when positioned upon the bed of the press.

In practising our invention we provide in each side of the chase 6 at a suitable distance from the upper end thereof horizontally extending apertures or recesses 11 and 12 at the inner terminations of which are bored vertical holes 13 and 14, which holes are screwthreaded for the reception of the hollow set screws 15 and 16. The points of these set screws are tapered as best shown at 17. Slidably mounted in the recesses 11 and 12 are the adjusting plungers comprising the heads 18 and the stems 19. The inner ends of the heads 18 are beveled at 20 and it is against these beveled faces that the tapered ends of the screws 15 and 16 bear so that as said screws are screwed downwardly the plungers will be forced outwardly. Projecting outwardly from the heads 18 are the stems 19 which are of a length such that when the screws are at their uppermost position and the plungers at their innermost positions the free ends will register with the outer edges of the chase. A collar 21 is pressed within the outer ends of the recesses 11 and 12 and surrounds the plunger stem 19 and mounted within these recesses between the plungers and said collar are coil springs 22 which act to hold said plungers in their innermost positions against the points of the set screws 15 and 16.

Formed at each end of the lower cross member 24 of the chase 6 are rectangular recesses

25 and 26 and in these recesses are mounted the height adjusting blocks 27 and 28. Rigidly mounted in each end of these blocks are dowel or guide pins 29 and 30 the free ends of which are loosely positioned within apertures 31 and 32 in said cross bar 24 of the chase 6. Blocks 27 and 28 are rigidly secured upon the outer ends of the stems 33 and 34 of the plungers 35 and 36. Plungers 35 and 36 are slidably mounted in recesses 37 and 38 in the lower ends of the side members of the chase 6. At the inner terminations of the recesses 37 and 38 are provided vertically extending screwthreaded holes 39 and 40 and in these holes are mounted the set screws 41 and 42. The points of screws 41 and 42 are tapered and bear against the beveled ends 43 and 44 of the plungers 35 and 36 so that as said screws are screwed downwardly the tapered points thereof bear against the beveled end of said plunger and force the same outwardly together with the stems and the blocks 27 and 28. A collar 45 is pressed within the outer ends of the recesses 37 and 38 and surrounds the stems 33 and 34 and coiled around said stems between said collars and the plungers 35 and 36 are coil springs 46 and 47 which act to hold said plungers in their innermost positions against the points of the set screws.

In the operation of our invention the chase is first positioned upon the bed of the press in the usual manner with the adjusting devices all in their closed positions as shown in Fig. 1. Should it be desired to raise the chase the set screws 41 and 42 will be rotated, by means of a suitable key or screw driver, downwardly when the tapered points will propel the plungers 35 and 36 outwardly and with them the blocks 27 and 28. Blocks 27 and 28 will bear against the abutments 9 and 10 which are rigid with the bed of the press and the chase will thus be forced upwardly. By unscrewing the set screws the springs 46 and 47 will be permitted to retract the plungers and blocks. Should it be desired to move the chase sidewise in either direction the set screw 15, 16 on the side of the chase opposite to the direction in which it is desired to move the chase will be screwed downwardly thus forcing out the respective stem 19 which will contact with the inner edge of the roller track and thus move the chase in the direction desired. Any one of the adjusting devices may be operated independently of the others or any combination thereof may be used.

From the foregoing it will be obvious that the chase may be easily and quickly adjusted in any direction and at any angle within its limits and securely locked to the bed of the press when so adjusted.

Having described our invention what we claim and desire to secure by Letters Patent is:

1. A platen press chase comprising a substantially rectangular frame adapted to have the type form locked therein, the lower corners of said frame being cut away to form recesses opening downwardly and outwardly, plungers slidably mounted in the side members of said frame longitudinally thereof to slide lengthwise of said side members, an adjusting block rigidly secured to the lower end of each of said plungers normally resting within said recesses; resilient means to normally hold said plungers and adjusting blocks in their innermost positions; and means to move said plungers and blocks outwardly.

2. A platen press chase comprising a substantially rectangular frame adapted to have the type form locked therein, downwardly and outwardly opening recesses formed in the lower corners of said frame, plungers mounted in the side members of said frame to slide longitudinally thereof, adjusting blocks rigidly secured to the lower end of said plungers and normally resting within said recesses; means to hold said plungers and blocks in their innermost positions; means to move said plungers and blocks outwardly; a plunger mounted in each of said side members above said first mentioned plungers slidable at right angles thereto, means to hold said last plungers in their innermost position, and means to move said plungers outwardly.

3. A platen press chase comprising a substantially rectangular frame adapted to have the type form locked therein, the lower corners of said frame having recesses formed therein, adjusting blocks slidably mounted in said recesses; plungers mounted in the side members of said frame extending and sliding longitudinally thereof to the lower ends of which said adjusting blocks are rigidly connected whereby said plungers and blocks move together, means to normally retain said plungers in their innermost position with the blocks within said recesses, means to move said plungers to cause said blocks to project from said recesses; plungers mounted in said side members extending and slidable at right angles to said first plungers, means to hold said plungers in their innermost positions, and means to cause the outer ends of said plungers to project beyond the sides of said frame.

4. A platen press chase comprising a substantially rectangular frame adapted to have the type form locked therein, the lower outer corners of said frame being cut away to form rectangular recesses opening outwardly, longitudinally extending apertures formed in the side members of said frame, opening at one end into said recesses and terminating at its other end a short distance below the transverse center of the side members, a screw threaded aperture extending from the upper face of said side members to and con-

necting with the inner termination of said longitudinal aperture, a screw threaded wedge mounted in said last aperture, plungers mounted in said longitudinally extending apertures having adjusting blocks mounted upon the outer ends thereof and having their inner ends terminating in wedge shaped heads adapted for cooperation with said wedge shaped screws whereby downward movement of said screws will move said plungers outwardly, springs coiled around said plungers within said apertures adapted to normally hold said plungers in their innermost positions, said adjusting blocks resting within said recesses, transverse apertures in said side members near the inner termination of said longitudinal apertures, opening outwardly, a screw threaded aperture extending from the upper face of said side members to the inner termination of each of said transverse apertures and connecting therewith, a screw threaded wedge mounted in each of said transverse apertures, a plunger mounted within each of said transverse apertures having its inner end tapered to cooperate with said screw threaded wedge whereby downward movement of said wedge will force said plunger outwardly, and a coil spring coiled around each of said last plungers within the transverse aperture adapted to normally hold said plungers at their innermost positions.

In witness that we claim the foregoing we have hereunto subscribed our names this 19th day of December, 1928.

GEORGE A. DICKLEY.
EARL B. GROFF.
